METAL WINDOW STRUCTURE

Adolf H. Schaffert, Youngstown, Ohio, assignor
to Truscon Steel Company, Youngstown, Ohio,
a corporation of Michigan

Application May 21, 1931. Serial No. 539,048

7 Claims. (Cl. 189—75)

Considerable difficulty is experienced with metal window frames made of deformed metal sheets or plates because of the liability of air to find ingress from the outside through the frame structure into the room.

One of the objects of the present invention is to provide an improved form of structure that more fully seals the joints against the passage of air, and at the same time produces a stronger structure than has heretofore been obtained.

Another and important object is to provide means for more effectively securing packing or calking material in place in the joints between the frame structure and the building wall in which such structure is located.

In the accompanying drawings:

Figure 1 is a cross sectional view through the jamb member of a window frame having the improved features.

20 Figure 2 is a sectional view on the line 2—2 of Figure 1.

Figure 3 is a perspective view of the section.

Figure 4 is a detail perspective view of a portion of the jamb box.

25 Figure 5 is a similar view of a portion of the cover strip for such jamb box.

Figure 6 is a perspective view of a portion of the staff bead.

30 Figure 7 is a similar view of a portion of the parting strip.

The jamb box proper consists of a sheet or plate of deformed metal, providing a rear wall 8, an inner side wall 9 and an outer side wall 10, the latter being narrower than the former. The 35 inner wall 9 terminates at its free margin in an inturned flange 11 having an outturned terminal portion 12 providing an inwardly opening groove 13. The outer wall 10 has an inturned flange 14 and the juncture of this flange with the wall 10 is in the form of an inset bead 15.

40 Secured to the flange 14 of the wall 10 of the jamb box is a staff bead. This also comprises a deformed metal strip or plate having a rear wall 16, an outer wall 17 and a facing wall 18 that is inturned from the outer wall 17 and spaced from the wall 16. It will be noted that the rear wall 16 is provided in its outer face with a longitudinal groove 19 formed by insetting the metal and this groove snugly receives the bead 15 formed at the juncture of the wall 10 and flange 14 of the jamb box. The flange 14 lies against the rear face of the wall 16 on the inner side of the tongue and groove interlocking engagement, and the parts are preferably secured together by 45 electrical spot welding, as indicated at 20. The

5 rear wall 16 on the outer side of the groove 19 is furthermore provided in its rear face with a relatively broad, and preferably shallow channel 21 that is thus located between the groove 19 and the outside wall 17.

60 The wall 16 of the staff bead extends inwardly into the jamb box and has a longitudinal groove 22 formed in its outer face. A cover strip 23 having a hooked inner margin 24 that interlocks with the hook and channel 11, 12—13 of 65 the rear wall 9 of the jamb box, has an inset portion 25 and an outturned wall 26 that lies against the inner portion of the wall 16 of the staff bead. This portion 26 is provided on its rear face with a longitudinal rib 27 that engages in the 70 groove 22 of the wall 16. Between the staff bead wall 18 and the cover strip 23 is located a parting strip comprising a facing wall 28 and rear walls 29 joined to the parting strip by out-set beads 30. The outer bead 30 cooperates with 75 the inner edge of the staff bead wall 18 to provide a guide slot 31. Similarly the inner bead 30 of the parting strip is spaced from the outer edge of the wall 23 to provide a guide slot 32. The parting strip is held in place by screws 33 80 passing through the facing wall 28 and having threaded engagement with the rear wall 16 of the staff bead. The side walls 29 of the parting strip preferably terminate in inturned bearing flanges 34 that bear against the wall 26 and thus 85 serve to secure the cover strip to the wall 16 and maintain an interlocking engagement of the bead 27 in the groove 22.

90 In Figure 1 there is shown portions of the sash, the same being designated 35. These sashes, as is well known, have outstanding flanges 36 that travel in the guideways 31 and 32.

95 It will be understood that by reason of the welding 20, the staff bead becomes a permanent part of the jamb box and when the frame is placed in position in a wall structure, the main body of the jamb box is preferably embedded in the wall. This wall may have a concrete body, as indicated at 37 and be faced with brick or 100 stone, as 38. The structure of the wall, however, constitutes no part of the present invention, but is shown in Figure 1 for illustrative purposes. The cover strip and parting strip are removable to permit the introduction and removal of the 105 sashes 35 and also to give access to the interior of the jamb box, in which the sash weights are located.

110 In this structure two outstanding features are to be noted. The interfitting of the wall 10 of

the jamb box and the wall 16 of the staff bead by reason of the tongue and groove connection 15—19 insures a weather-proof joint that more effectively prevents the passage of air into the 5 jamb box from the exterior of the building and consequently its escape into the room. More than that, the channel 21 on the outer side of the groove 15 in the wall 16 creates an enlarged chamber for the reception of calking or packing 10 between the walls 16 of the staff bead and the wall of the building. Therefore when calking or packing, as shown at 39 is forced into the joint between said wall 16 and the building wall 38, it fills the channel 21 and thus is locked in 15 place so that the danger of its dropping out is greatly lessened. Consequently a more effective seal is provided between the interior of the jamb box and the exterior of the building than has heretofore been available.

20 From the foregoing, it is thought that the construction, operation and many advantages of the herein described invention will be apparent to those skilled in the art without further description and it will be understood that various 25 changes in the size, shape, proportion and minor details of construction may be resorted to without departing from the spirit or sacrificing any of the advantages of the invention.

What I claim, is:

- 30 1. In a hollow metallic frame structure, the combination with a tubular jamb box, of a staff bead at the inner side of the same and having a portion including a back wall projecting outwardly beyond the same and adapted to lie along- 35 side the structural wall of the building, said projecting portion of the back wall having an inset portion forming a longitudinal channel in its rear face to receive and provide an interlock for calking material placed between the structural wall and the projecting portion of said 40 back wall of the staff bead.
2. In a hollow metallic frame structure, the combination with a tubular jamb box having an outer side wall, of a staff bead outstanding from 45 the side wall and having a rear wall provided in its rear face with a groove and a channel outside the groove, the side wall of the tubular jamb box having its free edge engaged in the groove, leaving the channel exposed for the reception of calking material that engages in and is held against displacement by the walls of said channel.
3. In a hollow metallic frame structure, the combination with a tubular jamb box having an outer side wall terminating along its free edge 55 in an inturned flange and having a tongue projecting beyond said flange, of a staff bead out-

standing from the side wall and having a rear wall provided in its rear face with a longitudinal groove and a longitudinal channel outside the groove, the said tongue of the side wall of the jamb box being engaged in the groove and said tongue and flange leaving the channel exposed for the reception of calking material that engages in and is held against displacement by the walls of said channel.

80

4. In a hollow metallic frame structure, a tubular jamb box and staff bead of deformed metal, including a rear wall and an inner or front wall provided with sash guideways, said rear wall having an inset depression forming on its interior side a reinforcing bead and providing in its outer side a groove for the reception of the material of the wall in which the frame structure is installed.

85

5. In a hollow metallic frame structure, a tubular jamb box of deformed metal having a rear wall, and a staff bead of deformed metal mounted on the outer side of the jamb box and projecting outwardly beyond the same, said staff bead also having a rear wall that extends outwardly beyond the jamb box, said rear walls 100 each having an inset depression forming on its interior side a reinforcing bead and providing in its outer side a groove for the reception of the material of the wall in which the frame structure is installed.

90

6. In a hollow metallic frame structure, the combination with a tubular jamb box having a rear wall and an outstanding side wall, of a tubular staff bead at one corner of the jamb box, said staff bead having an outer side wall located 110 outside the plane of the side wall of the jamb box and a rear wall that extends across the space between the two side walls and transversely across the outer end of the side wall of the jamb box, said rear wall of the staff bead having a groove 115 in its outer side and said outer end of the jamb box's side wall engaging in said groove.

105

7. In a hollow metallic frame structure, the combination with a jamb box having a rear wall, spaced side walls, one of said side walls being 120 narrower than the other, and a cover wall extending from the wider side wall, of a tubular staff bead located in advance of the narrower side wall and including an outer side wall located outside the same and a rear wall extending across 125 the free end of said narrow side wall and connected to the cover wall, said rear wall of the staff bead having a groove in its rear side and the free edge of the narrower side wall of the jamb box being engaged in the groove.
